UNITED STATES PATENT OFFICE.

JAMES ARCHIBALD MACALLISTER AND ELISHA FREDERICK STOCKUM, OF ASHLAND, WISCONSIN.

SHINGLE.

Application filed April 15, 1922. Serial No. 552,920.

To all whom it may concern:

Be it known that we, JAMES ARCHIBALD MACALLISTER and ELISHA FREDERICK STOCKUM, citizens of the United States, residing at Ashland, in the county of Ashland and State of Wisconsin, have jointly invented certain new and useful Improvements in Shingles, of which the following is a full, clear, and exact description.

10 The invention relates to building materials and has for its object the production of a new and improved type of shingle, for roofing, siding or other purposes.

This invention consists in the novel construction, arrangement and combination of parts, hereinafter more particularly described and claimed.

In accordance with the present invention, a stucco composition is applied to a core of 20 wood, felt, fibre or metal, so as to produce a shingle of weather-proof and fire-proof qualities and both useful and ornamental.

One sheet of drawings accompanies this specification as part thereof:

25 Fig. 1 shows the improved shingle.

Fig. 2 an assemblage of the unit form of shingle shown in Fig. 1.

Fig. 3 shows the method of assembling the unit form of shingle shown in Fig. 1.

30 Fig. 4 is a cross-section taken on line 4—4 of Fig. 2.

The numerals in the drawing refer to like parts in the several figures and specification. 1 indicates a shingle of wood, felt, fibre or metal; 2, 3 and 4 indicate the stucco coating on the side and bottom edges, respectively; 6 indicates the stucco coating on one of the faces; 5 indicates the upper edge of the core and 7 the surface to which the 40 shingles are applied.

The stucco is applied to the core by dipping, brushing or plastering, dependent upon the nature of the core, on both faces, the adjacent sides and the lower end and extending 45 over a major portion of the core. A portion of the core is left uncoated so as to provide for nailing or otherwise securing the shingles in place, but provision may also be made for nail holes through the stucco covered surface, if desired. The coating may be of any kind of stucco having the qualities of fire and water resistance, close adherence

to the core and rigidity. This improved shingle is applied to roofs, sidings and other surfaces in the manner customary with ordinary shingles, but being coated on both faces, sides and bottom edge with a protective coating having heat and moisture resisting qualities, is manifestly superior to the ordinary shingle, moreover, the coating 55 of both faces, sides and bottom edge with said protective coating for a major portion of the core, ensures in the assembling of the shingles complete protection for all exposed portions of each individual shingle. Furthermore, this improved shingle has obvious 60 advantages as a substitute for stucco applied by the ordinary method of plastering in building construction,—it provides all the advantages of stucco construction, but with 65 a known quality of composition and produces a more artistic effect; the units being of relatively small dimensions can be readily transported, handled and secured in place, and their use in lieu of ordinary plastered stucco will produce more substantial 70 structures at less cost.

A further advantage from the use of stucco as above set forth and described in connection with wooden shingles is the characteristic of stucco absorbing moisture in the setting and hardening process, which characteristic operates to draw any moisture from the wooden core and thus tends to eliminate warping of the core, which tendency is still further resisted after hardening of the stucco by its rigidity in connection with its close adherence to the surface of the core by reason of which moisture is 75 unable to enter.

Having thus fully described our invention, we claim:

1. A shingle for building construction having a core coated with stucco on two faces, its sides and bottom edge.

2. A shingle for building construction having a wooden core coated over a major portion of two faces, its sides and bottom edge with stucco.

3. A shingle comprising a wooden core 100 coated with stucco.

JAMES ARCHIBALD MACALLISTER,
ELISHA FREDERICK STOCKUM.
